(57) **CLAIM**

The ornamental design for a showerhead, as shown and described.

DESCRIPTION

In a preferred embodiment, the nature of this product is as a showerhead primarily useful for enabling a water spray from a plumbing fitting.

FIG. 1 is a left, top, front perspective view of a showerhead embodying my new design;

FIG. 2 is a bottom, front perspective view thereof;

FIG. 3 is a bottom plan view thereof;

FIG. 4 is a left side elevational view thereof, the right side elevational view thereof being a mirror image of the left side shown;

FIG. 5 is a top plan view thereof;

FIG. 6 is a bottom perspective view thereof;

FIG. 7 is a left, top, front perspective view of another embodiment of my new design which is identical to FIG. 1 except for the broken line representation of the pipe esutcheon; and,

FIG. 8 is a left side elevational view thereof, the right side elevational view thereof being a mirror image of the left side shown.

The broken line representations of a pipe and escutcheon in FIGS. 1-2 and 4-8, of rear wall structure in FIGS. 1, 5 and 7, and of a tab in FIGS. 1-8, are for the purpose of illustration only, and form no part of the claimed design.
